UNITED STATES PATENT OFFICE

WALTER K. DWELLE, OF HOUSTON, TEXAS, ASSIGNOR OF FORTY PER CENT TO JOHN T. DEAVER, TWELVE AND ONE-HALF PER CENT TO JAMES LAWLER, AND SEVEN AND ONE-HALF PER CENT TO C. C. CUNNINGHAM, ALL OF HOUSTON, TEXAS

FUSELAGE FOR AEROPLANES

Application filed October 17, 1927. Serial No. 226,714.

This invention relates to new and useful improvements in a fuselage for aeroplanes.

One object of the invention is to provide an aeroplane fuselage constructed with internal chambers to contain a light gas, such as helium, to render the craft buoyant.

Another object of the invention is to provide a fuselage having an air channel therethrough, through which the air from the propeller may be driven as the craft moves through the air, thus minimizing the resistance of the air, in front, against the craft, and assisting in the propulsion of the craft forwardly.

With the above and other objects in view this invention has particular relation to certain novel features of construction, arrangement of parts and use an example of which is given in this specification, and illustrated in the accompanying drawings, wherein:—

Figure 1 shows a fragmentary plan view of an aeroplane, embodying the invention, shown partly in section.

Figure 2 shows a fragmentary front elevation thereof.

Figure 3 shows a longitudinal sectional view.

Figure 4 shows a cross sectional view taken on the line 4—4 of Figure 3, and

Figure 5 shows a cross sectional view taken on the line 5—5 of Figure 3.

Referring now more particularly to the drawings wherein like numerals of reference designate similar parts in each of the figures the numeral 1 designates the fuselage, as a whole, and the numerals 2, 2 designate the plane, or wings. The number 3 designates a motor, of conventional construction, located in the forward end of the fuselage and having the forwardly extending propeller shaft 4.

An enclosed type of propeller should be employed, such as that shown in my copending application, executed and filed of even date herewith. The fuselage has an air channel 5 extending therethrough from the front to the rear end, whose forward end terminates in the inlet ports 6. The air in front of the craft, within the range of the propeller is collected and forced by the propeller, through the channel 5, thus forming a par-

tial vacuum in front of the craft and minimizing the air resistance thereto, and the reaction of the column of moving air through the channel 5 against the walls thereof assists in propelling the craft forwardly.

The aeroplane has the usual cockpit 7 with a storage chamber 8, beneath it and also provided with a long storage chamber 9 behind it, accessible through the side door 10.

Around the cockpit 7 and the chambers 8 and 9 there is an enclosed chamber 11, provided to contain helium or other light gas to contribute to the buoyancy of the aeroplane. The walls of the chamber 11 are braced by suitable cross braces, as 12.

While I have shown what I now consider the preferred form of the invention it is obvious that mechanical changes may be made therein and equivalents substituted for the parts shown and I hereby reserve the right to make such mechanical changes and adaptations as may be found practical or desirable so long as I do not depart from the principle of the invention as comprehended within the scope of the appended claim.

What I claim is:—

In an aeroplane, a fuselage having an air channel in the bottom thereof extending from end to end thereof and whose forward end is upturned and terminates in an air inlet port at the extreme front end of the fuselage, said fuselage having a cockpit with a storage chamber beneath it and a storage chamber behind it, above said air channel, said fuselage having a gas chamber on each side of the cockpit and entirely surrounding said storage chambers on each side and above, and cross braces reinforcing the walls of said gas chamber.

In testimony whereof I have signed my name to this specification.

WALTER K. DWELLE.
